TOY

Frank Hammond, Boonton, N. J.

Application September 24, 1940, Serial No. 358,046

10 Claims.

(Cl. 46—86)

This invention relates to toys in which a doll representing a man is provided with a pack for enclosing a folded parachute which is attached to the doll; and also with suitable timing and tripping mechanism adapted to release the parachute following the shooting of the doll upwardly into the air.

An object of the invention is to provide simplified means for positively liberating the parachute from the pack just as the doll reaches the peak of its upward flight.

Another object of the invention is to provide means for manually holding the mechanism in a cocked position when the toy is grasped by a hand to impel the same into the air.

A further object of the invention resides in means for automatically holding the mechanism in a partly cocked position so that the operation of packing the parachute may be accomplished with the use of both hands.

Another object of the invention is to provide means for adjusting the mechanism to change the timing increment in order to compensate for any lack of uniformity in the manufacture thereof, and also to effect the freeing of the parachute at the end of shorter or longer flights as may be desired.

Further objects and advantageous features of the invention will appear throughout the following specification.

The invention will be more fully understood by reference to the drawings forming a part of this specification, and in which,

Figure 1 is a rear elevation of my improved toy, partly broken away and partly in section, to show the mechanism to greater advantage, the flaps of the pack being indicated in broken lines in an open or extended position, and the mechanism being shown in a partly cocked position.

Figure 2 is a side elevation, partly in section, of the parts shown in Figure 1, but showing the parachute folded within the pack.

Figure 3 is an enlarged fragmentary section on the line 3—3 of Figure 2.

Figure 4 is a fragmentary elevation of the end of one of the flaps of the pack.

Figure 5 is a miniature elevation of the toy with the parachute extended.

Figure 6 is a view similar to Figure 1 showing a modified form of the invention.

Figure 7 is a view similar to Figure 3, but embodying the modification shown in Figure 6, and,

Figure 8 is a detail section on the line 8—8 of Figure 7.

Referring now in detail to the drawings, 10 represents the doll which is shaped to resemble an aviator having a body 11, head 12 and legs 13. It may be made of any suitable material, but cellulose acetate has been found to be appropriate because of its strength, durability, cheapness of manufacture, and adaptability to hollow-formation molding to reduce weight in order to preclude the necessity of too large a parachute to pack within the limited space available for this purpose.

A weight of approximately one ounce has been found to be practical for the effective shooting of the toy, and its proper rate of speed in descending.

The back of the doll is provided with a rectilinear recess 14 having sloping upper and lower walls 15 and 16, and straight side walls 17 and 18. The bottom wall 19 of the recess 14 has an opening 20 therethrough leading into the hollow interior of the doll, and which is closed by a rectangular plate 21 with the edges thereof overlapping the edges of the opening 20. Plate 21 may be secured to the doll by means of a bolt 22 which passes through it and is threaded into the front wall of the body 11.

The plate 21 is utilized to support on one of its sides a pack or casing 23 for enclosing a parachute P having shrouds P' secured to it in the conventional manner, and to the neck of the doll. On the other side of the plate there is supported a part of the parachute releasing mechanism which is thus located within the doll and hereinafter to be described.

The pack 23 is preferably made of cloth and consists of a single piece of material cut to provide four oppositely disposed flaps 24, 25, 26 and 27, respectively designated to correspond to the order in which they are consecutively wrapped over and about the folded parachute as shown in Figure 2, and which are indicated in broken lines in Figure 1 in an open position.

The pack may be secured to the outside surface of the plate 21 in any suitable manner, such for example, as by a proper adhesive. A clip 28 is attached to the outer extremity of the flap 27 as by prongs 29 passed through the cloth 27 and then bent as shown in Figure 4. The clip 28 is stepped, as at 30, for engagement with the lower edge of a slot 21' adjacent the top of plate 21, as shown in Figures 1, 2 and 3, to hold the parachute securely within the pack 23, as best shown in Figure 2.

Mechanism is provided for lifting the clip 28 from the position shown in Figure 2, to enable the flaps to fall away and liberate the parachute. For this purpose there is shown a cocking lever 31 pivoted on the inside of plate 21 at 32, and one end 31' of which projects beyond one side of the doll 10 through a slot 33. Lever 31 is pivoted adjacent its other end 31'', as at 34, to the upper end of a rod 35 having a piston 36 secured to its opposite end and slidable within a cylinder 37. Piston 36 is provided with a leather cup washer 36' which fits within the surrounding walls of the cylinder 37 loosely enough to by-pass air in either direction of its movement, but more freely during its downward movement.

Cylinder 37 is pivoted at its lower end, as at 38, to the plate 21, and its upper end is closed with a plug 39 through which the rod 35 may slide with a loose fit to permit the passage of air as well.

Lever 31 is provided with a plurality of notches 40 along its upper edge between the pivot 32 and its outer end 31', for selective engagement with the looped end of a coil spring 41, the opposite end of which is looped over the end of pivot 38 projecting beyond the cylinder 37.

From the foregoing it will now be apparent that lever 31 may be manually rocked from the position shown in dot and dash lines in Figure 3 to that shown in full lines, by lifting the end 31''. This movement stretches the spring 41 and lowers the piston 36 in the cylinder 37, and any air so displaced will be forced past the cup washer 36'. However, during the return movement of lever 31 under the urge of spring 41, a partial vacuum will be established below the piston thus retarding its upward movement in the cylinder commensurate with the power of the spring and the rate at which air can again pass the piston to permit it to slowly reach the end of its upward stroke. This retarded movement of the mechanism toward a position in which it can trip the clip 28 provides an interval of time during which the doll may reach a suitable altitude before the freeing of the parachute takes place.

Means are provided for latching the lever 31 in an intermediate position in which the mechanism may be held independently of the operator in what may be termed a half cocked or partly cocked position, as shown in Figure 1. Under such circumstances the piston 36 will be substantially midway in the cylinder 37, and the top edge of lever 31 will be sufficiently below the slot 21' so as not to interfere with the insertion and seating of the clip 28 therein. Accordingly an opportunity is then afforded the operator of the toy for the free use of both hands to fold the parachute back and forth in the conventional manner of pleating commonly practiced by parachute jumpers, and place it in the recess 14, and complete the pack by wrapping the flaps about the parachute, the insertion of flap 27 being the last step in the sequence. Clip 28 can then be inserted and the step 30 hooked over the rim of the slot 21'. The clip 28 has a tip 28' of sufficient length to overlie the plane in which lever 31 moves, and thus constitutes a trigger adapted to be engaged and tripped by lever 31 during the latter part of the upward movement of piston 36.

Means are also provided for manually holding the mechanism in a fully cocked position, as in Figure 3, until such time as the toy may be released to begin its upward flight.

The mechanism for both of these purposes consists of a latch lever 50 within the doll, which may be pivoted to the plate 21, but which is herein shown as pivoted at 51 to the front wall of the body 11. The lower end of lever 50 extends into the hollow legs 13 of the doll, and has an ear 52 which projects outwardly through a slot 53 in the side wall of one of the legs 13. The upper end 54 of lever 50 has a bevelled head 55 to facilitate the aforesaid latching operation, and the inner edge of the lever beneath the head is cut back to provide a shoulder 56. Beneath shoulder 56 there is provided a saw tooth 57 having oppositely sloping edges 57' and 57''.

The end 31'' of lever 31 is bent at a right angle inwardly so as to extend across the plane in which the latch lever 50 moves. A coil spring 58, one end of which is secured to the doll and the other end to lever 50, above pivot 51, urges the lever into the position shown in dot and dash lines in Figure 3.

It will now be apparent that lever 50 may be manually rocked on its pivot 51 by pressing on the ear 52, and that if lever 31 is also rocked with the other hand, an engagement of these parts may be effected in which shoulder 56 will overlie the end 31'' resulting in partly cocking the mechanism; and that such position of the parts will be maintained under the tension of spring 41 which obviously exceeds the power of spring 58.

After the packing of the parachute has been completed while the mechanism is in the position shown in Figure 1, the operator simply lifts the end 31' of lever 31 to the position shown in full lines in Figure 3 while grasping the legs of the doll with the other hand, thus pressing against the ear 52 and effecting an engagement of the end 31'' of lever 31 with the surface 57'' of lever 50. Lever 31 is thus manually held in a position in which the mechanism is fully cocked. During the aforesaid movement of lever 31, the sloping edge 57' of tooth 57 is first engaged by the end 31'' to thereby rock lever 50 slightly so that surface 57'' may be engaged.

Well known means for shooting the toy into the air, such as a stick with a rubber band attached, may then be utilized by hooking the band under the chin of the doll's head. Upon stretching the band by grasping the stick with one hand and the legs of the doll with the other, and then releasing the grip on the legs, lever 50 will be immediately retracted by the urge of the spring 58, and in consequence thereof lever 31 will be freed to be moved by spring 41, and the piston 36 will simultaneously start moving slowly upwardly in the cylinder 37, thus always ensuring the beginning of the timing movement of the mechanism at precisely the beginning of the flight of the toy.

The time required for the piston to reach its uppermost position in the cylinder 37 should substantially correspond to the interval of time required for the toy to reach its maximum height in the air. At such time the lever 31 will engage and release the clip 28, and the flaps will thereupon spring open and allow the parachute to fall outwardly, the sloping walls 15 and 16 providing an easier exit.

Should manufacturing tolerances cause variations in the degree of time required for the piston to reach the top of its stroke and thus cause the parachute to be released too early or too late, as the case may be, the spring 41 may be shifted to one of the notches 40 that is either nearer to or

more remote from pivot 32, in order to counteract such a condition. In the first instance the leverage would then be less favorable to the spring 41, so that the time interval would be increased, and in the second instance, the reverse would occur and lever 31 would be rocked more rapidly to shorten the time interval.

Referring to the modified form of the invention shown in Figures 6, 7 and 8, it will be noted that the cylinder 37, together with piston rod 35 and piston 36, have been mounted on the plate 21 in a reversed position so that the pivot 38 is now adjacent the top thereof. A lever 60 is provided in place of lever 31, which is loosely pivoted to the plate 21 at 61, and also to the piston rod 35 as at 62. Lever 60 is provided with an end 63 which extends through a slot 64 in the lower side wall of the body 11 just above the legs 13, and is suitably bent to provide a tip 65 for convenient engagement by the thumb of a hand, so that lever 60 may be thereby manually rocked in order to depress the piston 36, and in consequence thereof stretch spring 41, following which the parts will be in the position shown in Figure 6.

A slot 66, similar to slot 21', is located adjacent the lower end of plate 21, and the clip 28 is attached to the outer extremity of flap 26 instead of flap 27, because in this form of the invention flap 26 will be the last in sequence to be wrapped about the folded parachute to complete the loading of the pack.

It will be apparent that when the toy is projected from a hand as by the means described, and with the parts in the position shown in full lines in Figure 6, lever 60 now free of the hand will be actuated by spring 41, and move slowly under the retarding effect of the piston 36, until the parts assume the position shown in dot and dash lines. Just prior to reaching such position, lever 60 will engage the clip 28 and push it downwardly, thereby effecting a disengagement of same with the top edge of slot 66, so that flap 26 together with all the other flaps lying beneath same will be free to allow the parachute to spring out of the pack. It will be understood that the timing of the mechanism corresponds to that shown in the preceding figures of the drawings, and that lever 60 may also be provided with the notches 40 for the purpose already described.

In order to load the pack 23 and insert the clip 28 in the slot 66 with the more convenient use of both hands, means are provided for independently holding lever 60 in an intermediate position in which it cannot interfere with the clip. For this purpose an ear 67 is struck out of the plate 21 and bent upwardly to provide a hook adapted to be engaged by the inner end 68 of lever 60. After the loading of the pack has been completed and clip 28 has been positioned in the slot 66, lever 60 may be fully depressed and held by the grasp of the operator until the toy is projected.

Upon the return movement of lever 60 during the flight of the toy, no re-engagement with the ear 67 can occur because the pivotal connections of the parts are loose, and spring 41, being offset at an angle, tends to pull the end 63 toward plate 21 (Figure 7), thereby causing the end 68 to tilt away from the plate and the ear 67. Obviously the reverse must take place when it is desired to latch the lever 60 over and into engagement with the ear 67. This may be readily accomplished by a crosswise tilting of the lever as it is rocked by a thumb on its pivot 61 against the urge of the spring 41.

The structure shown in Figures 6, 7 and 8 pro-

vides a cheaper method of carrying out the invention without losing the advantage of latching the mechanism in a partly cocked position during the loading and clip setting operations.

As shown in Figure 6, the shrouds P' may be divided into two groups of three and secured to tapes 69, which are inserted in suitable openings through the shoulders of the doll on either side of the head 12 leading into the hollow interior of the body, and knotted to prevent their withdrawal.

It is obvious that other modifications may suggest themselves to persons skilled in the art, and be employed to secure substantially the same results without departing from the spirit of my invention. Therefore the foregoing description is illustrative and not intended as limiting the invention thereto. Changes in details of construction which are simply matters of form of design are to be considered within the scope of the invention.

I claim:

1. In a toy of the kind described having a parachute attached thereto, and a pack with flaps for enclosing the parachute when the same is folded, mechanism operative to open said pack at approximately the end of the upward flight of said toy into the air, including a lever for holding parts of said mechanism under tension in a cocked position when the toy is grasped by a hand, and being adapted to automatically release said parts at substantially the beginning of said flight when the toy is projected from a hand.

2. In a toy of the kind described having a parachute attached thereto, and a pack with flaps for enclosing the parachute when the same is folded, mechanism operative to open said pack during the flight of said toy, including a lever for holding parts of said mechanism under tension in a cocked position when the toy is grasped by a hand, and being adapted to automatically release said parts substantially at the beginning of said flight when the toy is projected from a hand, and means forming a part of said mechanism effective for changing the timing thereof to advance or delay the opening of said pack.

3. In a toy of the kind described having a parachute attached thereto, and a pack with flaps for enclosing the parachute when the same is folded, mechanism operative to open said pack at approximately the end of the upward flight of said toy into the air, including a lever for holding parts of said mechanism under tension in a cocked position when the toy is grasped by a hand, and spring means for automatically retracting said lever to release said parts at substantially the beginning of said flight when the toy is projected from a hand.

4. In a toy of the kind described having a parachute attached thereto, and a pack with flaps for enclosing the parachute when the same is folded, mechanism operative to open said pack at approximately the end of the upward flight of said toy into the air, including latching means for maintaining parts of said mechanism under tension in a partly cocked position during the loading of said parachute in said pack, and further means for holding said parts under greater tension in a fully cocked position when the toy is grasped by a hand, and being adapted to automatically release said parts at substantially the beginning of said flight when the toy is projected from a hand.

5. In a toy of the kind described having a parachute attached thereto, and a pack with

flaps for enclosing the parachute when the same is folded, mechanism operative to open said pack during the flight of said toy, including a lever for holding parts of said mechanism under tension in a cocked position when the toy is grasped by a hand, and means for adjusting said tension to advance or delay the opening of said pack.

6. In a toy of the kind described having a parachute attached thereto, and a pack for enclosing the parachute when the same is folded, means for securing the pack in a closed position, mechanism for automatically opening said pack at a predetermined time during the flight of said toy comprising a cylinder, a piston and piston rod for retarding the return movement of the mechanism, and a cocking lever connected to said piston rod adapted to trip said pack securing means, and to be manually actuated to move the piston in one direction, spring means for urging said piston in the opposite direction, and means for latching said cocking lever in an intermediate position during the loading of said pack, and adapted to be manually held in advance of such position when the toy is grasped by a hand.

7. In a toy of the kind described having a parachute attached thereto, and a pack for enclosing the parachute when the same is folded, means for securing the pack in a closed position, mechanism for automatically opening said pack at a predetermined time during the flight of said toy comprising a cylinder, a piston and piston rod, and a cocking lever connected to said piston rod adapted to trip said pack securing means, and to be manually actuated to move the piston in one direction, spring means for urging said piston in the opposite direction, a latch lever adapted to engage said cocking lever and hold same in an intermediate position during the loading of said pack, and also adapted to hold said cocking lever in an advanced position when the toy is grasped by a hand, and spring means for retracting said latching lever to automatically release said cocking lever when the toy is projected from a hand.

8. In a toy of the kind described having a parachute attached thereto, and a pack for enclosing the parachute when the same is folded, means for securing the pack in a closed position, mechanism for automatically opening said pack at a predetermined time during the flight of said toy comprising a cylinder, a piston and piston rod, and a cocking lever connected to said piston rod adapted to trip said pack securing means,

and to be manually actuated to move the piston in one direction, spring means for urging said piston in the opposite direction, a latch lever pivoted to said toy, and one end of which projects from same adjacent its lower extremity, and the other end of which is provided with means for effecting an engagement with said cocking lever when the same is advanced to an intermediate position during the loading of said pack, and also for holding said cocking lever in a further advanced position when said latch lever is manually held while the toy is grasped by a hand.

9. In a toy of the kind described having a parachute attached thereto, and a pack for enclosing the parachute when the same is folded, means for securing the pack in a closed position, mechanism operative to automatically open said pack at a predetermined time during the flight of said toy comprising a cylinder, a piston and piston rod for retarding the return movement of said mechanism, and a cocking lever for effecting relative movement of the piston within the cylinder in one direction to cock said mechanism, spring means for urging said parts in the opposite direction, and a lever provided with means adapted to hold said mechanism under the tension of said spring means when said lever is actuated by grasping the toy in a hand, and to release said mechanism when the toy is projected from a hand.

10. In a toy of the kind described having a parachute attached thereto, and a pack for enclosing the parachute when the same is folded, means for securing the pack in a closed position, mechanism operative to automatically open said pack at a predetermined time during the flight of said toy comprising a cylinder, a piston and piston rod for retarding the return movement of said mechanism, and a cocking lever for effecting relative movement of the piston within the cylinder in one direction to cock said mechanism, spring means for urging said parts in the opposite direction, and a lever provided with means for latching said mechanism under the tension of said spring means during the loading of said pack, and provided with further means adapted to subsequently hold said mechanism under said tension when said lever is actuated by grasping the toy in a hand, and to release said mechanism when the toy is projected from a hand.

FRANK HAMMOND.
